WINDSHIELD WIPER ELEMENT

Harry Roberts, 639 Bond Court,
Merrick, N.Y. 11566

Filed Jan. 29, 1968, Ser. No. 10,348

Term of patent 14 years

(Cl. D14—6)

Fig. 1

Fig. 2

Fig. 3

FIGURE 1 is a fragmentary top plan view, broken away to indicate indeterminate length, of a windshield wiper element showing my new design;

FIGURE 2 is a cross-sectional view taken about the line 2—2 in FIGURE 1;

FIGURE 3 is a fragmentary elevational view taken about the line 3—3 in FIG. 2.

I claim:

The ornamental design for a windshield wiper element, as shown and described.
